UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,024, dated May 27, 1884.

Application filed March 27, 1884. Term of patent 3½ years.

To all whom it may concern.

Be it known that I, SARAH JANE SHIELS, of the city, county, and State of New York, have invented and produced a new and original Design for a Pattern of a Lady's Costume, (numbered 9,189;) and I do hereby declare that the engraved prints accompanying this specification convey to any one accustomed to using paper patterns a clear understanding of how a garment made up by the pattern will appear.

The design shows a round walking-skirt and an overdress. The skirt displays a deep lower front drapery falling in draped points at the lower part, and an upper front drapery displaying shirrings at the center and back edges. The overdress exhibits short polonaise-fronts with buttons extending to below the

waist-line and displaying shirrings in their front and back edges, a closely-fitted polonaise-back exhibiting under-folded plaits at the lower ends of its middle three seams, draping-plaits in its front edges and loopings at the center, coat-sleeves reversed at the wrists in cuffs, and a standing collar.

What I claim as my invention, and desire to secure by Letters Patent, is—

The design for a lady's costume, as shown in the engraved prints accompanying this specification.

SARAH JANE SHIELS.
